SUPPORT FOR BRIDGES OF OVERHEAD TRAVELING CRANES

Ambrose Mazzola, Temple City, and Vermont V. Mappin, West Covina, Calif., said Mappin assignor to Calabar Corporation, South Gate, Calif., a corporation of California

Application December 27, 1954, Serial No. 477,808

11 Claims. (Cl. 105—148)

This invention relates to overhead traveling cranes and, more particularly, to a universal and expandable support for overhead traveling cranes.

Overhead traveling cranes fall into two broad categories, that is, underslung or suspended overhead traveling cranes, and top riding overhead traveling cranes. In disclosing the structure and mode of operation of our invention, it will be discussed as embodied in an underslung overhead traveling crane but it is, of course, not intended that those principles of the invention which are applicable to both types of overhead traveling cranes be limited solely to the underslung type.

As is well known to those skilled in the art, conventional overhead traveling crane installations usually include laterally spaced supporting rails upon which are engaged supporting members for the transversely oriented bridge structure extending between said supporting rails. In most installations, the lengths of the rails are substantial and, due to inevitable variations in the installation of said rails, there are differences in the spacing of the rails with respect to each other.

For instance, an individual rail may be slightly bowed or slightly cocked inwardly or outwardly. Attempts have been made in the prior art to overcome such discrepancies in the mounting of the supporting rails for overhead traveling cranes by suspending the rails from ball joint hangers which, to an extent, permit slight inward or outward movement of the rails with respect to each other as the crane bridge moves across the rails from one end to the other thereof. However, such prior art expedients are not utilizable in all applications and where inequality in the bracing of the supporting rails is encountered, undue loads are placed upon the transversely oriented bridge and the supporting means therefor disposed in engagement with said rails.

It is, therefore, an object of our invention to provide an overhead traveling crane wherein the supporting means engaging the supporting rails and the transversely oriented bridge of the crane are connected by universal joint means which permits the movement of the transversely oriented bridge structure of the crane with reference to the supporting means therefor to accommodate inequalities in the spacing of the supporting rails or inequalities in the rails themselves.

Another object of our invention is the provision of universal joint supporting means for the bridge structure of the aforementioned traveling crane which is constituted by ball and socket joint means disposed in operative relationship with the supporting means and adapted to mount the opposite ends of the bridge structure on said supporting means so that, by rotational movement of the ends of the bridge structure through said ball and socket joint, the variations in the spacing of the supporting rails and variations in the shape of the supporting rails will be automatically accommodated by relative movement between the ends of the transversely oriented bridge structure and their respective supporting means.

Of course, in most overhead traveling crane construc-

tions there is occasionally encountered a wide discrepancy in the location of the supporting rails and in conventional traveling crane constructions tremendous loads are imposed upon both the rails and their supports because of the inflexibility of the bridge structure supported upon said rails. Of course, the bridge structure is also subjected to undue loads when such wide variations in the location of the supporting rails are encountered.

Another object of our invention is the provision of an overhead traveling crane wherein the bridge structure is mounted upon supporting means engaging the supporting rails for said crane and wherein expansion joint means is provided between one end of the bridge structure and its respective supporting means to permit relative longitudinal movement between the supporting means and said one end of the bridge structure to take place in order that wide variations in the spacing of the supporting rails may be accommodated and undue loads frequently imposed upon the rails and bridge structure in conventional overhead traveling cranes be eliminated.

A further object of our invention is the provision of an overhead traveling crane of the aforementioned character wherein the expansion joint means is incorporated in the universal joint connection between said end and its associated supporting means so that both longitudinal and rotary movement of the transversely oriented bridge structure of the overhead traveling crane and its associated supporting means may take place to accommodate all inequalities which may be encountered during the translation of the crane from one end to the other of the supporting rails.

Another object of our invention is the provision of an overhead traveling crane of the aforementioned character wherein the supporting means for the transverse bridge structure is constituted by trolley means engaging the supporting rails and said trolley means includes load bars for supporting the opposite ends of the transversely oriented bridge structure.

Positioned between the load bars and the ends of the transversely oriented bridge structure are ball and socket joint connecting means which serve as the sole means of physical connection between the ends of the transversely oriented bridge structure and their respective supporting means.

A further object of our invention is the provision of an overhead traveling crane of the aforementioned character wherein the aforementioned load bars are, in turn, supported from the trolley wheels of the trolley means by ball joint means which permit the pivotal and rotational movement of the trolley wheels with respect to the load bars supported thereupon.

A further object of our invention is the provision of an overhead traveling crane which is characterized by its freedom from undue maintenance expense and repairs arising out of the failure of the supporting rails or the premature wear thereof.

Other objects and advantages of our invention will be apparent from the following specification and the accompanying drawings which are for the purpose of illustration only and in which:

Fig. 1 is a top plan view of an overhead, underslung traveling crane constructed in accordance with the teachings of our invention;

Fig. 2 is an end elevation of the crane shown in Fig. 1;

Fig. 3 is a side elevational view of an overhead traveling crane embodying the teachings of our invention;

Fig. 4 is an enlarged, fragmentary, sectional view showing the universal supporting joint for one end of the transversely oriented bridge structure;

Fig. 5 is a vertical sectional view taken on the broken line 5—5 of Fig. 4;

Fig. 6 is an enlarged, vertical, sectional view taken on the broken line 6—6 of Fig. 1;

Fig. 7 is an enlarged, vertical, sectional view taken on the broken line 7—7 of Fig. 1;

Fig. 8 is an enlarged bottom plan view of one of the sockets incorporated in the universal joint;

Fig. 9 is a top plan view of another of the sockets incorporated in the universal joint; and

Fig. 10 is a schematic view showing the relationship of the expansion joint with one end of the transversely oriented bridge in the overhead traveling crane of our invention.

Referring to the drawings and particularly to Figs. 1-3 thereof, we show an underslung overhead traveling crane 10 constructed in accordance with the teachings of our invention and suspended from parallel, laterally spaced supporting rails 12. A transversely oriented bridge structure 14 constitutes a part of the overhead traveling crane 10 and includes transversely oriented track members 16 which are rigidly secured at their opposite ends to elongated end trucks 18. The end trucks 18, as best shown in Figs. 1-4 of the drawings, include laterally spaced side frames 20 encompassing the respective supporting rails 12 and joined in operative relationship with each other by transversely oriented tie bars 22.

The end trucks 18 are mounted for movement on the rails 12 by means of supporting means 24, which will be adverted to in greater detail hereinbelow. Mounted on the tracks 16 is a hoist, or similar carriage 26. The hoist carriage 26 is substantially rectangular in configuration and is suspended from the tracks 16 by means of rollers 28, as best shown in Figs. 1 and 2 of the drawings, said rollers permitting the carriage 26 to be translated from one side to the other of the crane 10 by means of a drive motor 30 connected to a driving roller 31.

Supported upon the bed of the carriage 26 is a hoist motor 32 which is connected through a reduction gear, not shown, in a housing 34 to a hoist 36.

The supporting means 24 for the transversely oriented bridge structure 14 includes trolley means 38, said trolley means, as best shown in Figs. 2-7 of the drawings, including trolley wheels 40 engageable with the treads 42 of an associated supporting rail 12.

In the presently discussed embodiment of our invention, there are, of course, two end trucks provided at opposite ends of the bridge structure to which are rigidly secured two track members 16. To support the transversely oriented bridge structure 14 from the supporting rails 12, there are provided four supporting means 24, one at each end of an end truck of the bridge structure 14. However, it should be understood that in various applications the number of supporting means will vary, generally in proportion to the load which must be sustained by the bridge structure and it is, of course, not intended to limit the scope of the invention to the particular number of supporting means shown or to immaterial details of the construction thereof. This is, of course, also true of the bridge structure 14 since the bridge structure 14 can include any number of transversely oriented track members and can also include different relationships between the track members and the end trucks supporting the same.

The trolley wheels 40 are mounted upon axles 44 which are, in turn, mounted in the oppositely disposed ends of the oppositely disposed arms 46 of yokes 48, as best shown in Figs. 4 and 5 of the drawings. Supported from the longitudinally spaced yokes 48, as best shown in Figs. 4 and 5 of the drawings, is a load bar 50, said load bar being constituted by longitudinally extending side plates 52 maintained in operative relationship with each other by end plates 54 welded to, or otherwise operatively connecting, said side plates.

A pivot pin 56 extends through oppositely disposed openings in adjacent end plates 54 and has mounted 75

thereupon an elongated member 58 which has a spherically generated surface 60 provided thereupon, as best shown in Fig. 4 of the drawings, said spherically generated surface being supported in the bight 62 of the yoke with which it is associated. A retainer plate 64 extends transversely between the arms 46 of the yoke 48 and serves to retain the member 58 in operative engagement with the bight 62 of the yoke 48. A centering hole 65 is provided in the yoke adjacent the spherically generated portion 60 on the elongated member 58.

It is manifest, therefore, that, as the trolley means 38 traverses the tread 42 of the associated rail 12, pivotal movement about the axis of the pin 56 between the load bar 50 and the associated yokes 48 at the opposite ends thereof can occur. In addition, since the load bar 50 is supported from the yokes 48 by the spherically generated surface 60 on the elongated member 58, relative rotational movement in a horizontal plane between the opposite ends of the load bar 50 and the respective yokes 48 is permitted to take place. Moreover, relative rotational movement between the yokes 48 and the ends of the load bar 50 in a vertical plane extending through the axes of the pivot pins 56 can also take place, thus providing a universal action at the opposite ends of the load bar to partially accommodate for inequalities encountered by the trolley means 38 during the translation of the crane 10 and, more particularly, the bridge structure 14 thereof along the supporting rails 12.

Mounted intermediate the ends of the load bar 50, as best shown in Figs. 4, 6, and 7 of the drawings, is connecting means 66, said connecting means being constituted by a ball and socket joint 68. The socket 70 is secured between the side plates 52 by means of bolts and nuts 72 and provides a conical socket 74 for the reception of a ball 76.

Since there is a distinction in the type of socket provided in the right-hand end truck 18 from that provided in the left-hand end truck 18, as viewed in the drawings, the socket member 78 is the right-hand end truck 18 will be first described.

The socket member 78 provides a conical socket 80 and is secured by means of bolts and nuts 82 between flanges 84 secured to the underside of the side frames 20. Therefore, the ball 76 resting in the socket 74 of the socket member 70 is engaged in the conical socket 80 provided in the socket member 78. In this manner relative rotational movement between the supporting means 24 and the supported portion of the end truck 18 is permitted to take place, thus relieving the strains and stresses upon the elongated, transversely oriented bridge structure 14 by mislocation of the rails 12.

The socket member 78, as best shown in Fig. 8 of the drawings, is substantially rectangular in configuration and, as best shown in Fig. 7 of the drawings, is provided in its upper surface with an elongated socket 86 of frusto-conical cross section. Therefore, when the socket member 78 is installed by means of bolts and nuts 82 in the flanges 84 on the left-hand end truck 18, as viewed in Figs. 1 and 6 of the drawings, it is inverted to bring the elongated socket 86 into engagement with the ball 78 resting in the frusto-conical socket 74. Therefore, in addition to permitting relative rotational movement between the supporting means 24 and the end truck 18, the ball and socket joint 68 also permits of longitudinal movement between the end truck 18 and the supporting means 24 therefor.

In other words, the ball and socket joint 68 incorporating the inverted socket member 78 provides an expansion joint whereby relative longitudinal movement between the end truck and its supporting means may take place to accommodate significant mislocations in the supporting rails, thus eliminating the overloads imposed upon said rails and upon the transversely oriented bridge structure in conventional overhead traveling cranes.

It should be understood that the ball and socket joints

constitute the sole connecting means between the end trucks 18 of the transversely oriented bridge structure 14 and the supporting means 24 therefor so that a flexibility of movement is obtained between said supporting means and the end trucks which cannot be achieved in conventional structures of the character under consideration. Furthermore, relative rotational movement between the yokes 48 of the trolley means and the ends of the load bars 50 suspended thereby is also permitted because of the provision of the elongated member 58 and, more particularly, the spherically generated surfaces thereupon. Thus, both the ball and socket joints between the end trucks 18 and the supporting means 24 and the ball socket joints between the yokes 48 and the load bars 50 serve as universal joint means to permit substantial rotational movement in various planes of the component parts of the supporting means 24 with respect to the elongated bridge structures 14 supported thereby.

However, it should be understood that while the ball and socket means are shown in combination, it is conceivable that only the ball and socket means between the end trucks and the supporting means might be utilized in a particular application. While the combination of the ball and socket means between the yokes and the load bars with the ball and socket means between the end trucks and the supporting means constitutes the most desirable combination, the advantages of either construction will permit them to be used independently of each other.

There is shown in Fig. 10 of the drawings a schematic representation of the relationship between the conical sockets 80 of the ball and socket joints 68 and the elongated frusto-conical sockets 86 in the left-hand end truck of the elongated, transversely oriented bridge structure 14. It is clear from this schematic representation that, as the end trucks traverse the supporting rails 12, if any substantial variation in the spacing of the rails 12 is encountered, relative longitudinal movement between the end truck 18 and the supporting means therefor will be permitted by virtue of the expansion joint constituted by the elongated socket 86 provided in the ball and socket joint in the left-hand end truck 18.

We thus provide by our invention an overhead traveling crane which is characterized particularly by permitting relative movement between the supporting means included in the same and the transversely oriented bridge mounted on said supporting means. By virtue of the construction disclosed hereinabove, undue loads imposed in conventional structures upon the transversely oriented bridge structure and the supporting rails therefor are eliminated since variations in the spacing of the supporting rails are accommodated by relative movement between the transversely oriented bridge structure and the supporting means therefor.

We claim as our invention:

1. In an overload traveling crane, the combination of: a bridge, said bridge including transversely oriented rail means secured at its opposite ends to end trucks; laterally spaced rails extending parallel to the path of movement of said bridge; trolley means engaged with said rails; and universal joint means between said trolley means and said end trucks supporting said end trucks by said trolley means, said trolley means including load bars underlying the opposite ends of said end trucks and said universal joint means including a socket on each of said load bars, a socket on the underside of each of said end trucks in opposed relationship with said load bar sockets and spherical bearing members mounted in said opposed sockets.

2. In an overhead traveling crane, the combination of: a bridge, said bridge including transversely oriented rail means secured at its opposite ends to end trucks; laterally spaced rails extending parallel to the path of movement of said bridge; trolley means engageable with said rails, said trolley means including load bars disposed below said end trucks; and universal joint means between the

undersides of said end trucks and the upper sides of said load bars, said trolley means and said end trucks supporting said end trucks on said load bars, said universal joint means between the trolley means and end truck at one end of said bridge incorporating means allowing relative lateral movement between said end truck and trolley means independently of the other end truck and trolley means.

3. In an overhead traveling crane, the combination of: 10 a bridge, said bridge including transversely oriented rail means secured at its opposite ends to end trucks; laterally spaced rails extending parallel to the path of movement of said bridge; trolley means engageable with said rails; and ball joint means supporting said end trucks on said 15 trolley means, said ball joint means supporting one of said end trucks incorporating expansion joint means which allows independent relative lateral movement between said end truck and trolley means with respect to said other end truck and trolley means.

20 4. In an overhead traveling crane, the combination of: a bridge structure having transverse members rigidly secured to end members; laterally spaced rails disposed adjacent said end members; trolley means supported on said rails, said trolley means including load bars underlying said end members; and ball joint connecting means between said load bars; and said end members supporting said bridge on said rails, said ball joint connecting means including opposed sockets secured to said load bars and said end members and spherical bearings in said 30 sockets whereby said load bars may be displaced independently of one another and said end members.

5. In an overhead traveling crane, the combination of: laterally spaced supporting rails; translatable supporting means engaged with said rails, said supporting means 35 including load bars whose longitudinal axes extend parallel to said rails; ball joint connecting means operatively secured to the upper portions of said load bars, said ball joint connecting means including first sockets on said load bars and balls in said first sockets; and a 40 transversely oriented bridge structure having its opposite ends overlying said load bars and provided with second sockets engaged with said balls in said first sockets, sockets at one end of said bridge structure being longitudinally movable relative to each other for independent lateral movement between said one end of said bridge structure and said supporting means.

6. In an overhead traveling crane, the combination of: laterally spaced supporting rails; trolley means mounted on said rails, said trolley means including load bars; ball 50 and socket connecting means on said load bars; and a bridge having sockets in its opposite ends overlying and engaged with the ball and socket connecting means on said trolley means, said sockets at one end of said bridge being elongated whereby relative lateral movement between said one end and its associated trolley means independently of the other end of said bridge is accomplished.

7. In an overhead traveling crane, the combination of: laterally spaced supporting rails; trolley means mounted on said rails, said trolley means each including spaced 60 trolley wheels engaging said rails and supporting a load bar therebetween; ball and socket connecting means on the upper portions of said load bars; and a bridge structure having its opposite ends superimposed upon and secured to said load bars by said ball and socket connecting means, the sockets on the trolley means supporting one end of said bridge structure being elongated whereby relative movement between said one end and said trolley means independently of its other end is accomplished.

8. In an overhead traveling crane supportable on laterally spaced rails, the combination of: movable supporting means engaging said rails, said supporting means including load bars; a transversely oriented bridge structure extending across said rails in overlying relationship with said load bars; and connecting means securing said bridge structure to said load bars, said connecting means

7 including ball and socket means having an expansion joint between one end of said bridge structure and associated load bars whereby relative lateral movement between said supporting means and said one end independently of the other end of said bridge is accomplished.

9. A construction for supporting the bridge structure of an overhead crane between a pair of horizontally spaced substantially parallel supporting rails, including a load bar and trolley assembly carried by each of said supporting rails, comprising a member provided on said bridge structure overlying each of said load bars, pairs of complementary sockets, one socket of each pair being an upwardly directed socket formed on a load bar, the other socket of each pair being a downwardly directed socket formed on the said member overlying such load bar, a ball engaging each pair of sockets, said balls forming the connections between said load bars and said bridge structure.

10. The construction defined in claim 9 further characterized by at least one of said load bar and trolley 20

assemblies including a universal connection between the load bar and each trolley forming a part of such assembly.

11. The construction defined in claim 9 wherein one of the sockets of at least one of said pair of sockets has a dimension in a direction transverse to said supporting rails greater than the diameter of the said ball engaged thereby.
